(57) **CLAIM**

The ornamental design for a hospital kimono, as shown and described.

DESCRIPTION

FIG. 1 is a top perspective view of a hospital kimono, showing my new design;

FIG. 2 is a top plan view thereof;

FIG. 3 is a bottom plan view thereof;

FIG. 4 is a side elevational view thereof;

FIG. 5 is a front elevational view thereof;

FIG. 6 is a rear elevational view thereof;

FIG. 7 is a front elevational view thereof, showing in open condition. The broken line showing is for illustrative purposes only and forms no part of the claimed design.

FIG. 8 is a front elevational view thereof, shown in partially open condition; and,

FIG. 9 is a front elevational view thereof, of a second embodiment, shown in partially open condition.
